US0D1095745S

(12) **United States Design Patent** (10) **Patent No.:** **US D1,095,745 S**
(45) **Date of Patent:** **** Sep. 30, 2025**

(54) **ARTIFICIAL BAIT**

(71) Applicant: **Chao Liu**, Weihai (CN)

(72) Inventor: **Chao Liu**, Weihai (CN)

(**) Term: **15 Years**

(21) Appl. No.: **29/927,103**

(22) Filed: **Feb. 2, 2024**

(30) **Foreign Application Priority Data**

Jan. 23, 2024 (CN) 202430044829.6

(51) **LOC (15) Cl.** **22-05**

(52) **U.S. Cl.**

USPC **D22/133**

(58) **Field of Classification Search**

USPC D22/125, 126, 130, 131, 132, 133;

43/42, 42.1, 42.21

CPC A01K 85/00; A01K 85/005; A01K 85/021;

A01K 85/14

See application file for complete search history.

(57) **CLAIM**

The ornamental design for an artificial bait, as shown and described.

DESCRIPTION

FIG. 1 is a front, bottom and right side perspective view of an artificial bait, showing my new design;

FIG. 2 is a rear, top and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the artificial bait that form no part of the claimed design.

1 Claim, 8 Drawing Sheets
